UNITED STATES PATENT OFFICE.

LE ROY COMPTON, OF WAUKESHA, AND FRANCIS E. GALVIN, OF PORTAGE, WISCONSIN.

FLASH LIGHT.

Application filed January 15, 1926. Serial No. 81,402.

This invention relates to improvements in flashlights, and has primarily for its object to provide means whereby the lamp socket may be adjusted in various directions with 5 relation to the handle or casing.

Incidental to the foregoing, another object is to provide an attachment for conventional types of flashlights, whereby the lamp socket is rendered adjustable in various 10 directions without material alteration of the light.

With the above and other objects in view, which will appear as the description proceeds, the invention resides in the novel construction, combination and arrangement of parts substantially as hereinafter described and more particularly defined by the appended claims, it being understood that such changes in the precise embodiment of the 20 herein disclosed invention may be made as come within the scope of the claims.

In the accompanying drawing is illustrated one complete example of the physical embodiment of the present invention constructed according to the best mode so far devised for the practical application of the principles thereof.

Figure 1 is an elevational view of one form of the present invention, wherein the same is applied to a flashlight of conventional structure.

Figure 2 is a sectional view taken on the line 2—2 of Figure 1.

Referring now more particularly to the accompanying drawings, the numeral 1 designates a casing or handle, which in the conventional structures of flashlights is adapted to contain the dry cell batteries. In conventional lights a lamp head 2 is employed, which head is threaded upon the top of the casing 1 and carries a lamp as well as a lens 3.

The present invention, which is designed to render the lamp bulb head adjustable in various directions with relation to the handle or casing 1, comprises a cap 4, which is adapted to replace the lamp head 2 and is threaded upon the top of the casing 1.

Projecting from the cap 4 is an ear 5 to which is pivotally connected a threaded support for the lamp head 6 by means of a pair of lateral ears 7 and a rivet 8 passing through the ears 7 and the ear 5 of the cap 4. For the purpose of holding the support in adjusted position, it is proposed to use a pair of spring washers 9 which tend

to hold the ears 7 into frictional engagement with the ear 5. While one form has been illustrated and described for holding the support 6 in adjusted position, it will 60 be obvious that various other means may be employed for accomplishing the same purpose.

For the purpose of receiving the lamp head 2, the adjustable support 6 is provided with a threaded end corresponding to the threaded end of the casing 1 which normally carries the head 2. Thus it will be seen that in the form of the invention illustrated and described, wherein the same 70 is designed as an attachment, it may be readily attached to the conventional type of flashlight by removing the ordinary lamp head 2 and threading the cap 4 upon the casing. The lamp head 2 is then threaded 75 upon the adjustable support 6, which support is provided with an electrical connection 10 secured to the cap 4 whereby a lamp contained in the head 2 may be illuminated in any of its adjusted positions. 80

The cap 4 is provided with a spring clip 11 which cooperates with the handle or casing 1 to enable the light to be attached to a pocket, or any other desired object.

While we have shown the clip 11 as an 85 integral part of the cap 4, it will be appreciated that the same may be carried directly by the casing 1 or attached to the cap 4 by various means.

From the foregoing it will be seen that a 90 very simple mechanism has been provided which will effectually serve to render the conventional lamp head adjustable with relation to the handle whereby the rays of light may be directed at any desired angle. 95 While the foregoing has its obvious advantages, the same is of greater importance where it is desired to attach the light to the pocket, or other object, thus permitting the operator to have his hands free and at the 100 same time enable him to adjust the light in any desired direction.

We claim:

1. The combination of a conventional flashlight having a casing and having a 105 detachable lamp head, an attachment comprising a cap slipped over and locked to the upper end of the said casing and having a projecting ear, a movable threaded support having a projecting ear pivotally 110 secured to said first mentioned ear and receiving the lamp head, whereby said attach-

ment may be applied to the conventional flashlight and permit the lamp head to project either axially from said casing or at an angle to the axis of said casing.

- 5 2. The combination of a flashlight having a casing provided with an externally threaded portion at its upper end, and a lamp head provided with a threaded portion, an attachment comprising a cap internally threaded
10 to receive the threaded portion of the casing, said attachment having a projecting spring finger cooperating with the casing to provide a retaining grip therefor and

having a projecting ear, a movable threaded support receiving the threaded portion of ¹⁵ the lamp head and having an ear pivotally secured to said first mentioned ear, and flexible conductors extending from said movable support to said cap.

In testimony that we claim the foregoing we have hereunto set our hands at Waukesha, in the county of Waukesha, State of Wisconsin, and Portage, county of Columbia, and State of Wisconsin, respectively.

LE ROY COMPTON.
FRANCIS E. GALVIN.
